RALPH I. MEADER, OF LYNBROOK, NEW YORK

DESK CLIP FOR HOLDING BLANKS

Application filed July 17, 1929. Serial No. 378,852.

This invention relates to holding devices for a pile of blanks, such as telegraph blanks, adapted to engage the blanks along one edge and permit the top blanks to be readily removed without disturbing the pile beneath. Such devices are most commonly used for holding telegraph blanks while the printed strips containing the messages are gummed thereon. The blanks are loose or unattached to each other, and after pasting on one message the operator lifts the top blank and pulls it obliquely free from the holding device. It is desirable that this operation leave the remaining blanks in the pile unmoved.

The present invention aims to provide an improved device for this purpose. Heretofore a prolonged flexible strip has been arranged to bear upon the edge portion of the blanks, and adjustable springs have been arranged to act through levers to press down such strip upon the blanks. The present invention enables the flexible strip to be dispensed with, and avoids any necessity for spring adjustments. It also makes the operation of the device more uniform, positive, and convenient, and the construction more compact.

The preferred embodiment of the invention is shown in the accompanying drawing, wherein—

Figure 1 is a perspective view of the desk and blank-holding clip.

Fig. 2 is a plan of the clip with its top plate removed.

Fig. 3 is a section on the line 3—3 in Fig. 2.

Fig. 4 is an elevation partly in section, on the line 4—4 in Fig. 2.

Fig. 5 shows the three springs of differing length before being introduced into the chambers shown in Fig. 4.

Referring to the drawing, *a* is a supporting member on which a pile of blanks may be placed in the position indicated by the dotted lines *b*' in Fig. 1, with their top edges gauged by a strip *c*, and their right-hand edges by a strip *d*, their left-hand edges being held by the desk clip indicated as a whole at *A* in Figure 1. The gauge strip *c* may be undercut on its forward edge to hold the

blanks in an oblique pile to facilitate detaching the upper blank.

In the operation of such devices the supporting member *a* is fastened down to a desk or bench, where the operator may conveniently work over the uppermost blank to paste on the strip carrying the printed message. A pile of blanks having been put in position, the gummed strips are moistened and applied in successive lines to the top blank, and when this operation is finished the operator detaches the lower right-hand corner of the top blank and, lifting it free from the stop gauge *d*, pulls it diagonally downward and to the right, and thereby progressively detaches its left-hand edge from the grip of the clip *A*. The desideratum is that this clip shall so hold the blanks as to permit the pulling out in this manner of the upper blank without disturbing the remaining blanks of the pile, so that the operator may proceed to paste the message onto the next blank without loss of time.

Heretofore the clips has had a single holding member consisting of a flexible or yielding strip bearing down upon the left-hand edge of the blanks and pressed against them with varying pressures by springs (usually three) exerting a pressure upon the strip which increases from its upper to its lower end. Difficulty has been found in applying such elastic strip and in graduating the pressure. The best apparatus heretofore used has required long springs passing entirely beneath the blanks on the supporting member *a*, and having long adjusting screws on the right adjustable beneath the supporting member.

According to the present invention the clip *A* is formed of a plurality (preferably three) of presser feet, each having preferably an elongated engagement with the margin of the top blank, and the successive feet forming a nearly continuous elongated holding member, the feet being pressed against the blanks yieldingly by springs acting through levers in such manner as to give a nearly uniform bearing-down pressure against the blanks, whether the pile of blanks be thick or thin. The successive presser feet are

adapted to bear with varying frictional engagement upon the blanks, so that the one nearest the upper corner shall exert the least retarding effect, while that toward the lower corner has the greatest retarding effect. They are also arranged in stepped relation, so that the upper one engages a narrower margin of the blanks, and the lower one a wider margin. When three presser feet are employed, the middle one has an arrangement and function intermediate that of the others.

The preferred construction is that shown; wherein the presser feet are lettered e , e' , e'' , each being formed as a lever f pivoted on a rod g , and each of the three presser feet having an elongated bearer portion h . The levers f have each a long arm forked to engage and carry the foot or bearer portion h , and a short arm receiving the upward stress of a spring j , the three springs j being confined in chambers in a casing k and pressing upwardly through a disk l and plunger m against the short arm of the lever. The springs thus act at a decided mechanical disadvantage, which in practice may be even greater than that shown in Fig. 3, so that the difference in compression of the spring between a full pile of blanks and after it has been reduced to only one blank, need not exceed 5 per cent. This insures a practically uniform stress upon the blanks irrespective of the thickness of the pile. The variation in pressure applied through the levers to the bearer portions h of the successive feet e , e' , e'' , is best accomplished by cutting the three springs j , which otherwise are alike, to slightly different lengths, so that when forced into position in the spring chambers in the casing k , they will be under graduated stresses, whereby to press down the foot e with the least stress, and the foot e'' with the most, the intermediate foot e' having an intermediate stress. This construction eliminates all adjustment of the springs and makes a very simple device which is extremely compact and requires no attention during use.

The bearer portions h of the presser feet are preferably so nearly aligned as to accomplish a nearly continuous engagement with the blanks, but are stepped, as clearly shown in Fig. 2, so that the bearing portion of the upper foot e engages only a narrow margin of the blanks, while the others engage progressively wider portions of the margin. This facilitates pulling off of the top blank. As the top blank is pulled outward, it first disengages itself from the upper foot e , while the two others continue to hold down the pile of blanks; as soon as it has slipped out from under the first foot, this drops down onto the blanks and holds them while the top blank is being pulled from beneath the second foot, during which time the pile is held by the upper and lower

feet; and finally the blank, having been pulled free from the middle foot, is drawn out from under the lower foot while the other two are holding the pile of blanks. Thus at all times the pile of blanks is held under pressure independently transmitted by at least two of the three feet. It is important to observe that the three feet are structurally independent, each receiving the stress from its own spring and each transmitting bearing-down pressure to the blank independently of the others.

Owing to the differing spring stresses applied to the successive presser feet, the latter together constitute an elongated holding member for the blanks and individually hold the blanks with varying degrees of frictional engagement, thereby exerting a lesser retarding effect on the blanks toward their upper ends, and a greater retarding effect toward their lower ends.

Overlying the levers f is a single plate p having lateral ears q turned down and engaging the pivot rod g , so that this plate may turn on the rod as a lever. As the plate closely overlies the levers f , it serves as a means for simultaneously rocking these levers to lift the presser feet for the introduction of a new pile of blanks. To do this the operator presses downward on the left-hand portion of the plate p , so that through this plate pressure is transmitted to the shorter arms of the three levers which are thereby rocked against the stress of their springs.

The entire clip device is self-contained and is distinct from the supporting member or table a . The spring case k is formed on a supporting blank r which has upright ears s for receiving the pin g , and is fastened to the table a by screws or bolts t , as clearly shown. There are no other extraneous parts, no exposed springs, and no spring-adjusting means.

An advantage of the stepped arrangement of the presser feet is that it is no longer necessary to pull out the top blank by a diagonally downward pull, as a pull directly to the right will serve the purpose.

What I claim is:

1. A desk clip for holding a pile of loose blanks, comprising a supporting member adapted to locate the blanks, and an elongated holding member mounted on the supporting member, engaging one edge portion of the blanks, with means for pressing it down yieldingly against the pile of blanks, said holding member formed in a plurality of steps, all bearing upon the blanks and projecting to successively varying distances beyond the located edge of the blanks.

2. A desk clip for holding a pile of loose blanks, comprising a supporting member having means for locating the blanks thereon and an elongated holding member mounted

on said supporting member engaging one edge portion of the blanks, with means for pressing it down yieldingly against the blanks, said holding member comprising a plurality of presser feet each bearing upon the blanks, said feet projecting to varying distances beyond the edge of the blanks and engaging the blanks in stepped relation.

5. A desk clip for holding a pile of loose blanks, comprising a supporting member and an elongated holding member mounted on said supporting member engaging one edge portion of the blanks, with means for pressing it down yieldingly against the blanks, said holding member comprising a plurality of presser feet each bearing upon the blanks, said feet projecting to varying distances relatively to the blanks, and engaging a narrower margin of the blanks at one end and a broader margin at the other.

10. A desk clip for holding a pile of loose blanks, comprising a supporting member and an elongated holding member mounted on said supporting member, engaging one edge portion of the blanks, with means for pressing it down yieldingly against the blanks, said holding member comprising a plurality of independently movable levers having laterally-extended presser feet, each bearing 15 upon the blanks, said feet projecting to different lengths to successively engage wider marginal portions of the same blank.

15. A desk clip for holding a pile of loose blanks, comprising a supporting member and an elongated holding member mounted on said supporting member engaging one edge portion of the blanks, with means for pressing it down yieldingly against the blanks, said holding member comprising a plurality of presser feet each bearing upon the blanks, said feet having prolonged engaging portions bearing on the blanks, and stepped out of line with one another so as to overlap the marginal portion of the blanks to different 20 distances, and said pressing means acting to differentially stress the successive presser feet.

25. A desk clip for holding loose blanks, comprising a supporting member and an elongated holding member, mounted on the supporting member, engaging one edge portion of the blanks, with means for pressing it down yieldingly against the blanks, said holding member comprising a plurality of 30 separate presser feet all bearing upon the blanks, each formed as a lever having long and short arms, the long arm carrying the bearer portion, and the yieldable means differentially stressing the respective presser feet, and comprising springs mounted on the supporting member and imparting stress to the respective short arms.

35. A desk clip comprising a supporting member and a plurality of presser feet each formed as a lever, coiled springs stressing

the short arms of said levers, said springs being of different lengths, and a body portion mounted on the supporting member to which said levers are pivoted, having spring chambers of uniform lengths in which said 40 springs are confined, whereby the springs impart differing stresses to the respective levers.

45. In witness whereof, I have hereunto signed my name.

RALPH I. MEADER.
